US00D985603S

(12) **United States Design Patent** (10) **Patent No.:** **US D985,603 S**
Walecka et al. (45) **Date of Patent:** **** May 9, 2023**

(54) **DISPLAY SCREEN WITH A GRAPHICAL USER INTERFACE**

(71) Applicant: **MusicSketch, LLC**, Atherton, CA (US)

(72) Inventors: **John Lawrence Walecka**, Atherton, CA (US); **John Edward Walecka**, San Francisco, CA (US); **Aleksey Novicov**, Palo Alto, CA (US); **Michael Dewey Burks**, Menlo Park, CA (US); **Pablo Castellanos Macin**, Mexico City (MX)

(73) Assignee: **MUSICSKETCH, LLC**, Atherton, CA (US)

(**) Term: **15 Years**

(21) Appl. No.: **29/800,055**

(22) Filed: **Jul. 19, 2021**

(51) **LOC (14) Cl.** **14-04**

(52) **U.S. Cl.**

USPC **D14/486**

(58) **Field of Classification Search**

USPC D14/489-495, 485-488

(57) **CLAIM**

The ornamental design for a display screen with a graphical user interface, as shown and described.

DESCRIPTION

The sole FIGURE is a front view of the display screen with a graphical user interface.

The outermost broken lines showing an electronic device depict the environment of the claimed design and form no part of the claimed design. The remaining broken lines illustrate a display screen and portions of the graphical user interface that form no part of the claimed design.

1 Claim, 1 Drawing Sheet

1. A display screen with a graphical user interface, comprising:
